UNITED STATES PATENT OFFICE.

FRANKLIN P. BURNHAM, OF MIDDLETOWN, OHIO.

DESIGN FOR A SPROCKET-WHEEL.

SPECIFICATION forming part of Design No. 27,148, dated June 1, 1897.

Application filed April 16, 1897. Serial No. 632,517. Term of patent 14 years.

To all whom it may concern:

Be it known that I, FRANKLIN P. BURNHAM, a citizen of the United States, residing at Middletown, in the county of Butler and State of Ohio, have invented and produced a certain new and useful Design for Sprocket-Wheels, of which the following is a specification.

My invention relates to a new design for a sprocket-wheel for velocipedes, bicycles, and the like.

My invention is illustrated in the accompanying drawings, wherein—

Figure 1 is a side view of the sprocket-wheel embodying my invention. Fig. 2 is a section through the same.

This sprocket-wheel consists of a hub A, of any suitable description, and rim B, provided

with the teeth for the sprocket-chain, and the connecting part or parts C, connecting the hub and rim together, said connecting parts being dish-shaped or bent out of line with the hub and rim. The connecting-piece C may be of one continuous piece or may consist of a series of arms or spokes. 25

The essential feature of my design is the sprocket-wheel with the dish-shaped or bent connecting piece or pieces C, which connect the hub and rim of the wheel together.

I claim—

The design for a sprocket-wheel herein shown and described. 30

FRANKLIN P. BURNHAM.
